US00D999222S

(12) **United States Design Patent** (10) Patent No.: **US D999,222 S**
(45) Date of Patent: **** Sep. 19, 2023**

(54) **DISPLAY SCREEN OR PORTION THEREOF WITH GRAPHICAL USER INTERFACE**

(71) Applicant: **WATERS TECHNOLOGIES IRELAND LIMITED**

(72) Inventors: **Tudor Teisanu**, Brasov (RO); **David Gadsby**, Rochdale (GB); **Sean Power**, Salford (GB); **Jack Carpenter**, Holliston, MA (US)

(73) Assignee: **Waters Technologies Ireland Limited**, Dublin (IE)

(**) Term: **15 Years**

(21) Appl. No.: **29/734,458**

(22) Filed: **May 12, 2020**

(51) LOC (14) Cl. **14-04**
(52) U.S. Cl.

USPC **D14/486**

(57) **CLAIM**

The ornamental design for a display screen or portion thereof with graphical user interface, as shown and described.

DESCRIPTION

The FIGURE is a front view of a portion of a display screen with a graphical user interface showing our new design. The broken lines in the FIGURE show features of the graphical user interface that form no part of the claimed design.

The outer solid-line perimeter depicts a portion of a display screen and is included in the claimed design.
